UNITED STATES PATENT OFFICE.

ANTHONY PHERSON, OF ROCHESTER, NEW YORK.

WORK-BOX.

SPECIFICATION forming part of Letters Patent No. 579,652, dated March 30, 1897.

Application filed September 14, 1896. Serial No. 605,785. (No model.)

To all whom it may concern:

Be it known that I, ANTHONY PHERSON, a citizen of the United States, and a resident of Rochester, in the county of Monroe and State 5 of New York, have invented certain new and useful Improvements in Work-Boxes, of which the following is a specification, reference being had to the accompanying drawings, forming a part thereof, in which similar numerals 10 of reference indicate corresponding parts wherever found throughout the several views.

This invention relates to ladies' work-boxes; and the object thereof is to provide a device of this class which comprises a suitable box 15 or casing having a hinged box-shaped cover provided with pivoted spool-racks, which are designed to hold spools of thread, the construction and arrangement being such that when the box is open or the cover raised the 20 racks will be held in such position that the spools may be removed therefrom or placed thereon.

The invention is fully disclosed in the following specification, of which the accompanying drawings form a part, in which—

Figure 1 is a perspective view of my improved work-box with the cover raised and thrown back; Fig. 2, a transverse section adjacent to one end with the cover closed, and 30 Fig. 3 a sectional detail on the line 3 3 of Fig. 2.

In the practice of my invention I provide a box or casing 5, which is preferably oblong and rectangular in form and which may be 35 composed of any desired material. The box or casing is provided with a hinged box-shaped cover 6, the depth of which is about that of the thickness of the largest spool of thread, and secured to one end of said cover and to 40 the inner side thereof is a metal plate 7, and a similar metal plate 8 is secured to the opposite end, as shown in dotted lines in Fig. 1. I also provide spool-racks 9 and 10, each of which consists of a plate 11, provided with 45 rods or pins 12, and the plates 11 are pivoted between the end plates 7 and 8, and said plates 11 of the spool-racks are each provided at one end with a cross-head 13, each of which is provided with a backwardly-directed flange 50 14, to which the plates 11 are secured, and said cross-heads 13 project backwardly and upwardly and are connected by a rod 15,

which is curved at each end and passed through said cross-heads, as shown at 16, so as to form a pivoted connection, and the cross-head 13 of the plate 11 of the rack 10, which is situated adjacent to the hinges 16 of the cover, is provided with an arm 17, which is of the form of an ogee curve and which is provided with a longitudinal slot 18, which is 60 similar in form, and secured to the adjacent end of the box or casing 5 is a headed pin 19, which passes through said slot.

In practice the pins 12 of the rack 10 are preferably made longer than those of the rack 65 9, so as to accommodate spools of greater length; but this arrangement is not essential, and the pins of the rack 9 may be made longer than those of the rack 10, if desired.

The spools are placed upon the pins 12 of 70 each of the racks, as will be readily understood, and when the cover of the box or casing is raised and turned backwardly into the position shown in Fig. 1 the pins 12 will project vertically and the spools may be removed 75 or placed on said pins whenever desired; and when the cover is closed the racks are turned backwardly in such manner that the pins 12 thereof project parallel with the end pieces of the cover and about centrally thereof, as 80 shown at the right of Fig. 2, and no matter how the box or casing is handled when the cover is closed the spools cannot come off or be detached from the racks, the outer side 19 of the cover serving to retain the spools on 85 the rack 9, and the plate 11 of the rack 9 serving to retain the spools on the rack 10.

The above-described movement of the racks is accomplished by means of the arm 17, and the rod 15, which is pivotally connected with 90 the cross-head 13, and the box or casing, is also preferably provided with a longitudinal partition 20, but said box or casing may be divided in any desired manner, and the separate compartments formed therein may be 95 used as receptacles for articles of various kinds and classes.

My improved work-box may be made of any desired material and of any desired shape or form, and it is evident that changes in and 100 modifications of the construction herein described may be made without departing from the spirit of my invention or sacrificing its advantages.

Having fully described my invention, I claim as new and desire to secure by Letters Patent—

1. A box or case constructed as herein described, and provided with a hinged box-shaped cover in which are pivoted spool-racks, said spool-racks being pivotally connected by means of a rod, and one of said racks being provided at the end thereof, with an arm in which is formed a slot, through which projects a pin secured to the end of the box, as and for the purpose set forth.
2. A box or case constructed as herein described, and provided with a hinged box-shaped cover in which are pivoted spool-racks, said spool-racks being pivotally connected by means of a rod, and one of said racks being provided at the end thereof, with an arm in which is formed a slot, through which projects a pin secured to the end of the box, said racks consisting of longitudinal plates provided with pins which project upwardly when the cover is turned back, and

which are folded within said cover, when the latter is closed, as and for the purpose set forth.

3. The herein-described work-box comprising a body portion which is rectangular in form, and provided with a hinged cover which is similar in form, said cover being provided with pivoted spool-racks arranged longitudinally thereof, and pivotally connected by means of a rod at one end thereof, and one of said racks being provided with a curved arm in which is formed a curved longitudinal slot, through which projects a pin secured to the adjacent end of the box, substantially as shown and described.

In testimony that I claim the foregoing as my invention I have signed my name, in presence of the subscribing witnesses, this 11th day of September, 1896.

ANTHONY PIERSON.
